UNITED STATES PATENT OFFICE.

HOWARD M. STEPHENS, OF BOSTON, MASSACHUSETTS, ASSIGNOR TO THE
RICE & HUTCHINS, INCORPORATED, OF SAME PLACE.

DESIGN FOR A SHOE.

SPECIFICATION forming part of Design No. 26,307, dated November 17, 1896.

Application filed October 1, 1896. Serial No. 607,617. Term of patent 7 years.

To all whom it may concern:

Be it known that I, HOWARD M. STEPHENS, a citizen of the United States, residing at Boston, in the county of Suffolk and State of Massachusetts, have invented and produced a new and original Design for a Shoe, of which the following is a specification, reference being had to the accompanying drawings, illustrating my design, in which—

10 Figure 1 is a side view of a shoe, showing my design. Fig. 2 is a top view of the same. The leading feature of my design consists in the shape of the top of the upper A of the shoe, which is made with a swell or roll b extending around the outer side of its upper

15

edge, said roll being of transversely convex form, as shown in Fig. 1, and imparting to the top of the shoe an exceedingly novel and unique appearance.

What I claim as new, and desire to secure 20 by Letters Patent, is—

The design for a shoe, substantially as herein shown and described.

Witness my hand this 30th day of September, A. D. 1896.

HOWARD M. STEPHENS.

In presence of—

P. E. TESCHEMACHER,
FRANK A. PAGE.
